GAME

Jacobus G. Schoonderwoerd and Josephus R.
Houtman, Enka, N. C.

Application March 26, 1940, Serial No. 326,094

6 Claims. (Cl. 273—134)

This invention relates to amusement devices and more particularly to a game involving members movable on a board, the movement of such members being chance controlled.

Games of this broad general character have long been known and as employed today usually consist of a board having a number of spaces, the defining margins of which are printed to designate runways thereon, and a separate playing piece is provided for movement on each runway. In playing, the pieces are raced across the course laid out, the number of spaces over which a piece is moved in any single turn of a player being determined by a chance produced number. Generally hazards are provided in the course so that a playing piece coming to rest on the hazard will be penalized and consequently progress in the race will be delayed to the advantage of the other players.

While games of this character are amusing for a time, they have several disadvantages. For example, if dice are used as the chance controlled means for determining the movement of the playing pieces, only the total reading, determined by adding together the readings on the various dice, is of importance; while the combinations thrown are of negligible importance. Furthermore, the playing pieces being separate from the board, are apt to become lost, thus rendering the game no longer usable.

It is an object of this invention to provide a new parlor game involving movable pieces permanently attached to the playing board, while the game itself involves an entirely new combination between a playing piece and the chance controlled means for determining its movement.

It is contemplated by the present invention that the playing board have indicia thereon arranged in a progression and adapted to be consecutively disclosed by chance controlled means capable of producing each of the indicia of the progression. Consequently a new and interesting feature is added to a game of chance, namely the consecutive production of indicia in a progression.

The playing board of the present invention is adaptable for use by almost any number of players, is compact, strong and readily constructed.

The game lends itself to a wide variety of modifications and may be played either quickly or slowly as the players may desire while either individual or team play is possible of attainment.

Other objects and advantages of this invention will be apparent from a consideration of the following detailed description of preferred forms thereof in conjunction with the annexed drawings wherein:

Figure 1 is a plan view of one form of playing board constructed according to the present invention showing one of the masking slides par-

tially withdrawn and dice in their receptacle in the center of the board;

Figure 2 is a view in section taken along the line 2—2 of Figure 1; the dice being removed;

Figure 3 is a view in section taken along the line 3—3 of Figure 1;

Figure 4 is a fragmentary view in plan of a modified form of playing board constructed according to this invention; and

Figure 5 is a view in section taken along the line 5—5 of Figure 4.

From a further consideration of the drawing, particularly Figures 1 to 3 thereof, it will be seen that the apparatus for playing the game consists of a playing board and three dice associated therewith in a novel manner.

The playing board is of a laminated construction and includes a base lamina 10, cut in the form of a regular hexagon, a plurality of intermediate laminae 11, cut in triangular form, and a top or covering lamina 12 corresponding generally in configuration to base lamina 10. These laminae are suitably fastened together in superimposed relationship with the edges of the intermediate laminae 11 defining a plurality of radial runways 13. Usually it is desirable to cut all of the intermediate laminae 11 from a single sheet in a single operation so that a small hexagonal section with an annular recess may be provided at 14 to cooperate with top lamina 12 in defining the side walls of a dice receptacle 15.

To reinforce and assist in holding the laminae in superimposed position, a binding consisting of a thin metal strip 16 U in cross-section is clamped around the margins of the board. The upper or overlying margin of strip 16 is partially cut away at each of the runways 13 and bent down over base lamina 10 so that masking slides 17 may be mounted in the runways for reciprocation in radial paths. Each masking slide 17 is provided with an upstanding portion 18 which serves as a handle.

Underneath each slide 17 there are a series of radially disposed numerals on base lamina 10 these numerals being consecutive from 1 to 9, the highest number being most remote from dice receptacle 15. An aperture 19 is provided in top lamina 12 for registry with each of the numerals on the base, such numerals being observable through apertures 19 when slide 17 is moved outwardly as can be seen in Figures 1 and 2. Dice 20, 21 and 22 are thrown by the players in determining the movement of slides 17.

The modification of the playing board illustrated in Figures 4 and 5 is also used in conjunction with dice 20, 21 and 22. The modified board consists of a hexagonal base lamina 23 and a superimposed lamina 24 suitably fastened together and reinforced by a U-strip 25 corresponding in function and structure to strip 16 disclosed in Figures 1 to 3 inclusive. Lamina 24

is provided with a central annular opening and a plurality of radially disposed annular openings, one of which is disposed adjacent each corner of the board. The central aperture defines the margins of a dice receptacle 26 corresponding in function to receptacle 15.

An annular disc 27 is mounted in each radially positioned annular opening in lamina 24, said discs being fastened by pins 28 passing centrally therethrough and through base lamina 23 to render each disc rotatable about its respective pin as an axis. Each disc 27 is provided with a handle 29 which may be gripped for effecting rotation of the disc.

On the base lamina 23, a series of numerals and associated arrows are disposed in annular paths underlying discs 27. These numerals are normally masked by the disc, but are selectively observable in consecutive order through an oval opening 30 in each disc by rotating said disc. Note that oval opening 30 is of sufficient size to permit the viewing of a single number and one of its associated arrows. The numerals, as in the case of the embodiment of the board illustrated in Figures 1 to 3 inclusive, are consecutively arranged and consist of the digits from 1 to 9.

In playing the new game by the employment of the board shown in Figures 1 to 3 inclusive, each player selects a slide which he will try to move all the way out and back in again before his competitors can do the same thing, the movement of the slide being determined according to dice throws, as will be hereinafter explained. It will be noted that three conventional dice are disclosed so that it is possible to secure, in a single throw, any number from 1 to 18 by reading individual numbers as well as cumulative numbers determinable by adding together the readings on the dice. Due to the fact that the numerals on base lamina 10 are consecutively arranged, and consequently can be disclosed only in consecutive order by movement of slide 17, before slide 17 can be moved it is necessary to throw a "1". Thereafter movement can be effected only by throwing consecutive numbers, failure to throw such a number resulting in loss of turn to the next adjacent player.

By way of example, suppose that at the beginning of a game the first player secures in a single throw the indicia disclosed on dice 20, 21 and 22. This, at the beginning of the game, is the best throw because the slide 17 could be moved out to disclose the numeral "7" on base lamina 10 by the following calculations:

Movement to disclose "1" because die 22 reads "1";

Movement to disclose "2" because die 20 reads "2";

Movement to disclose "3" by adding together the readings on dice 20 and 22;

Movement to disclose "4" because die 21 reads "4";

Movement to disclose "5" by adding together the readings on dice 21 and 22;

Movement to disclose "6" by adding together the readings on dice 20 and 21; and

Movement to disclose "7" by adding together the readings on dice 20, 21 and 22.

Following this throw a player would have to throw a combination of 2 or 3 dice which would, when added together read 8. Failure to do so results in loss of turn to the next adjacent player who will attempt to throw the dice to secure a "1"

and as many more consecutive numbers as possible. After the numeral "9" has been disclosed the same procedure is followed in moving the slide back to starting position, it then being necessary to secure consecutive numbers each lower than the preceding number by calculating from the dice according to the procedure outlined above. The first player to fully withdraw and return his slide is the winner of the game. If it is deemed desirable to add a penalty feature to the game, a rule of absolute silence may be imposed on each player after his slide has reached the extreme outer position, i. e., has uncovered the numeral "9" and is ready to commence the return of the slide. The usual penalty is to move the slide to starting position thus forcing the offender to begin anew.

Of course any chance controlled means for securing numbers which will include each of the numbers on base lamina 10 may be used instead of dice and two dice may be employed for a slow game while to speed the play four or more dice may be used. Note that one die could not be used since no number higher than 6 could be attained. The number of numerals on the board may of course be either reduced or increased, although the numbers must be consecutive in a progression. Naturally the number of slides may be varied at will to accommodate any reasonable number of players. Partners may play by each moving his own slide until one is returned, the partner having finished then being permitted to retain his turn and throw dice for the movement of the slide which has not yet fully covered its path of reciprocation.

If the game is played on the board shown in Figures 4 and 5, the rules and possible modifications are the same as those discussed above, the consecutive numbers being disclosed by movement of discs 27 so that oval openings 30 will register with the numerals on base lamina 23. To avoid confusion in play resulting from the fact that each disc 27 will be moved first in a clockwise direction until the numeral "9" is disclosed and then in a counterclockwise direction back to numeral "1", two direction arrows are associated with each numeral, one of which and the adjacent numeral may be disclosed through the oval aperture. Thus when movement in a clockwise direction is begun the number and the arrow pointing to the right will be disclosed. When the player's next turn comes he will know at once the direction in which the disc is to be moved.

While preferred forms of this invention have been disclosed and described, it is intended that the invention be limited only in the light of the prior art and within the spirit of the appended claims.

What is claimed is:

1. In a dice game of the type wherein an object is moved on a board under the control of the readings of a plurality of dice thrown simultaneously, a board, a plurality of sets of indicia thereon, each set being radially arranged the components of each set of indicia forming a progression, and countersunk independent masking means operatively associated with each set of indicia, each of said masking means being movable to uncover only in sequence the components of said progression, whereby a masking means may be moved by a player to uncover in sequence all of the consecutive components of the progression producible by reading a single die or by adding together the readings of any of the dice.

2. In a dice game of the type wherein an object is moved on a board under the control of the readings of a plurality of dice thrown simultaneously, a board having a plurality of radially extending channel grooves therein, an identical set of consecutive numerals printed in the bottom of each groove, the lowest numeral in each instance being adjacent the axis of the board, and masking slides mounted for reciprocation in said grooves, said slides being adapted to uncover said numerals only in sequence, whereby a masking slide may be moved by a player to uncover in sequence all of the consecutive numerals thereunder which are producible by reading a single die or by adding together the readings of any of the dice.

3. A game board consisting of a base lamina, a covering lamina, intermediate laminae, means for holding said laminae in superimposed relationship, radially disposed identical sets of consecutive numerals printed on said base lamina, said covering lamina having an aperture therein adapted to register with each of said numerals, said intermediate laminae consisting of a series of sections the edges of which define runways adjacent each of said sets of numerals, and a mask reciprocal in each of said runways to consecutively disclose the numerals on said base lamina, said covering lamina having a large central aperture therein, the defining edges of which constitute defining edges of a central playing field for dice the bottom of which field is the base lamina.

4. In a dice game of the type wherein an object is moved on a board under the control of the readings of a plurality of dice thrown simultaneously, a board having a plurality of identical sets of consecutive numerals thereon, the component numerals of each set being consecutively arranged in an annular path, disc-shaped masking means overlying each of said sets of numerals and being rotatable to uncover the numerals only in sequence, whereby a masking means may be moved by a player to uncover in sequence all of the consecutive components of the progression thereunder which are producible by reading

a single die or by adding together the readings of any of the dice.

5. In a dice game of the type wherein an object is moved on a board under the control of the readings of a plurality of dice thrown simultaneously, a board consisting of a base lamina and a top lamina, means for holding said lamina in superimposed relationship, said base lamina having a plurality of identical sets of numerals thereon, the numerals composing each set being consecutively arranged in an annular path, each numeral having oppositely directed arrows positioned adjacent thereto on opposite sides thereof, said covering lamina having an aperture therein adapted to disclose each set of numerals and a mask rotatable in each of said apertures, said mask being adapted to disclose consecutively only one of the numerals composing the set and one of its adjacent arrows, whereby the mask may be moved by a player to uncover in sequence all of the consecutive components of the progression thereunder which are producible by reading a single die or by adding together the readings of any of the dice.

6. In a dice game of the type wherein an object is moved on a board under the control of the readings of a plurality of dice thrown simultaneously, a symmetrical polygonal board, a plurality of sets of indicia thereon, one set lying adjacent each corner of the board in one of a plurality of equal radial sectors thereof, each set of indicia being disposed in the same relative position with respect to its corner as every other set, the components of each set of indicia forming a progression, and countersunk independent masking means operatively associated with each set of indicia, each of said masking means being movable to uncover only in sequence the components of said progression, whereby a masking means may be moved by a player to uncover in sequence all of the consecutive components of the progression producible by reading a single die or by adding together the readings of any of the dice.
